UNITED STATES PATENT OFFICE.

PAUL BOYTON, OF CHICAGO, ILLINOIS.

COASTER.

SPECIFICATION forming part of Letters Patent No. 535,938, dated March 19, 1895.

Application filed January 25, 1895. Serial No. 536,185. (No model.)

To all whom it may concern:

Be it known that I, PAUL BOYTON, a citizen of the United States, residing at Chicago, in the county of Cook and State of Illinois, have 5 invented a new and useful Improvement in Coasters, of which the following is a specification.

My invention relates to the class of coasters wherein an inclined plane provided with 10 tracks is erected adjacent to a body of water and terminates at its lower end at or just below the surface thereof, and in which boat-shaped toboggans are caused to descend the inclined plane and continue under the impetus 15 acquired along the surface of the water, the boats being so constructed as to deflect the water from their sides to prevent it from splashing the occupants. The pastime afforded by coasters of this character has become 20 a very popular one of late, and is known as "shooting the chutes."

As features of the construction of the coaster it is necessary to make provision for conveying pleasure seekers to the elevated platform 25 from which the descent is made, and also for returning the boat-shaped toboggans to the same point. Heretofore the practice has been to draw the boats up the inclined plane by means of a cable or chain, and to 30 draw the pleasure seekers up the inclined plane in specially constructed cars also connected to a cable.

My present improvements relate to means for returning the boat-shaped toboggans to 35 the starting-platform by elevating them at the terminus of their course over the water to a sufficient altitude and then causing them to pass overhead along one or more cables to the starting-platform; and my invention consists in the general and specific mechanism by 40 which this is effected.

Referring to the drawings—Figure 1 is a sectional elevation of the entire structure; Fig. 2, an end elevation of the tower and boat-elevating machinery; Fig. 3, an enlarged detail view showing a gripping carrier for the boats mounted upon the overhead cable, and Fig. 4 an end elevation of the same.

A is the starting-platform and B the inclined plane both mounted upon suitable trestle work C, and D is a body of water, natural or artificial, at which the inclined plane termi-

nates. No further description of these features is deemed necessary since they are in substantial accordance with Letters Patent 55 of the United States, No. 411,255, granted to John P. Newburg on the 17th day of September, 1889.

E is a tower erected at the terminus of the course of the boats over the water and of such 60 height as to extend above the level of the starting-platform, and F is a cable connecting the top of the tower with the starting platform.

G G are elevator belts, two at each side, mounted upon sheaves H and H' on shafts v 65 at the top and bottom of the tower, and I is an engine operating, as by means of the belts indicated by dotted lines in Fig. 2, to revolve the sheaves H' in unison.

K K are the boat-shaped toboggans. 70

Each elevator-belt G is provided on its face with a series of hooks u and the upper edge of each boat-shaped toboggan is in the form of a hook-shaped flange t to engage the hooks u. Each boat, moreover, is provided at its 75 bow and stern with roller-tackle L, L' for connecting it with the cable, and the tackle L is provided with a grip M to serve as a brake. This is shown in detail in Figs. 3 and 4. Each roller s, s' and s² of the tackle and brake is a 80 grooved roller in order that it may maintain its place upon the cable F, and the gripping-roller s² is mounted eccentrically upon its shaft r so that by moving the handle q the cable may be gripped or released as desired 85 to control the movement of the boat. A common bearing N serves for the tackle roller and the gripping device. The lowest roller s³ serves as a pulley for the rope p which is provided with a ring o and branches n connecting it with the sides of the boat to preserve 90 the balance. The purpose of the pulley is to permit the attendant to raise and lower the boat with reference to the overhead cable.

The operation is as follows: A boat K with 95 its occupants having shot from the starting platform down the incline, passes along the surface of the water and is guided by its attendant into the space between the elevator-belts in the tower and this causes the hook-shaped flanges t of the boat to overhang the hooks u upon the elevator-belts. At this time 100 the movement of the belts has been stopped, either by stopping the machinery or releasing

a suitable clutch, and this occurs, of course, as often as a boat is to be connected; and any of the occupants who do not desire to pass with the boat back to the starting-platform, 5 may be landed, and others desiring to do so may take their places. Thereupon the elevator belts are started, when the hooks *u* engage the flanges *t* of the boat and raise it. When the boat has nearly reached the top the movement of the belts is stopped and the attendant places the supporting tackle *I*, *L'* upon the cable *F*. Thereupon by means of the ropes *p*, pulleys *s*³ and rings *o*, one of which is provided at each end of the boat, he raises the 15 latter clear of the hooks *u* and secures it there, and then, by a movement of the handle *q*, releases the gripping brake and allows the boat to proceed on its descent to the starting-platform. Here the tackle is released and the 20 boat is in condition for a fresh journey. For those not desiring to reach the starting-platform by the course just described, other means are provided. The drawings show elevators *O* for this purpose, but instead of these the 25 usual cars drawn up the inclined plane by a cable may be employed.

The drawings show a single cable *F*, but if desired two cables may be provided, thus giving greater safety to the moving boat. Obviously, the only change that this would involve would be the duplication of certain portions of the supporting-tackle. It will be found desirable to cause the elevator belts to stop and start periodically at intervals which will permit several boats if desired to be in course of elevation at the same time; and it is desirable to have the starting always take place at a signal from the attendant of the boat which is at the top of the tower in order that it may 35 not occur before he has his tackle fully adjusted. My invention, however, contemplates 40

the use of any suitable apparatus for lifting the boats and connecting them to a single or double cable for the purpose described.

What I claim as new, and desire to secure 45 by Letters Patent, is—

1. In combination with a coaster and with a body of water adjacent to the lower end of the inclined plane thereof, and boat-shaped toboggans adapted to slide down the said 50 plane and float upon the surface of the water, a tower at the terminus of the course of the boats extending above the level of the starting-platform of the coaster, an elevator for conveying the boats to the top of the tower, 55 a cable connecting the top of the tower with the starting-platform of the coaster and roller tackle for connecting a boat with the cable whereby it may pass by gravity from the top of the tower to the starting-platform, substantially 60 as described.

2. In combination with a coaster comprising a starting-platform *A*, inclined plane *B*, boat-shaped toboggans *K* and body of water *D* adjacent to the lower end of the inclined plane, 65 means for returning the boat-shaped toboggans to the starting-platform consisting of the tower *E* extending above the level of the platform, an elevating device in the tower, engaging means for detachably connecting 70 each boat with the elevating device, an inclined cable extending from the top of the tower to the starting-platform, roller-tackle for supporting the boat upon the cable and permitting it to pass by gravity to the starting platform and brake-mechanism upon the tackle for regulating the speed, substantially 75 as described.

PAUL BOYTON.

In presence of—

H. V. SEYMOUR,
J. N. HANSON.
